[57] CLAIM

The ornamental design for a model of the universe with
planets and stars, as shown.

DESCRIPTION

FIG. 1 is a bottom plan view of a model of the universe
with planets and stars showing my new design;

FIG. 2 is a front elevational view thereof taken in the
direction of arrow 2 in FIG. ;

FIG. 3 is a side elevation view thereof taken in the
direction of arrow 3 in FIG. 1;

FIG. 4 is a rear elevation view thereof taken in the
direction of arrow 5 in FIG. 4; and,

FIG. 5 is an opposite side elevational view thereof taken
in the direction of arrow 6 in FIG. 1.

FIG. 2

FIG. 6

FIG. 3

FIG. 4

FIG. 5
